WILLIAM M. VENABLE, OF PITTSBURGH, PENNSYLVANIA.

PHONOGRAPH RECORD AND RECORD BLANK AND METHOD OF MAKING THE SAME.

Application filed March 6, 1920. Serial No. 363,746.

To all whom it may concern:

Be it known that I, WILLIAM MAYO VENABLE, a citizen of the United States, residing at Pittsburgh, in the county of Allegheny and State of Pennsylvania, have invented certain new and useful Improvements in Phonograph Records and Record Blanks and Methods of Making the Same, of which the following is a specification.

This invention relates to phonograph records and to the blanks from which they are made and also to an improved method of producing them, and it is the particular object of this invention to make the method of producing the blanks and the records therefrom cheap and simple and at the same time extremely satisfactory in the results obtained. I particularly aim to make my method or process readily available for the use of amateurs, the actual production of a record from a blank made in accordance with my invention being, in fact, so simple that it is comparable to the taking, developing and finishing of an amateur snapshot. The blank made by the method which is described hereinafter can be used by an amateur in making records without requiring special skill or knowledge simply by following a few directions and carrying out a few operations, no more, if indeed quite as difficult as the developing and printing of a photographic picture.

I intend to manufacture these blanks for use upon the ordinary and well known disc phonograph of which there are on the market, many types, any one of which could be used in connection with making a record from a blank produced by my method. The amateur desiring to make a record on one of my blanks will require a simple recording apparatus which must be designed so that it can be applied to an ordinary disc talking machine and I have provided such an apparatus which, however, as it forms no part of the present invention, is not described nor illustrated herein. The present invention has particular reference to the blank and to the method by which I produce it and in their preferred embodiments these are illustrated in the accompanying drawings, wherein:

Fig. 1 is a cross section through the disc and through a tray in which cooling may be carried on in accordance with my

method; Fig. 2 is a cross section through a finished blank having a coating or film of wax which has been applied in accordance with my method; Fig. 3 is a cross section through a blank having a film of wax and a crust of graphite; Fig. 4 is a section like that of Fig. 3 illustrating diagrammatically a recording instrument and the manner in which the undulatory sound line is cut in the wax and graphite; Fig. 5 is a greatly enlarged cross section through a small portion of a blank prepared with wax and graphite illustrating the character of the groove cut by the stylus; and Fig. 6 is a plan view of the lower or recording end of the stylus. It will be understood, of course, that in these figures the film of wax and the crust of graphite are shown considerably out of proportion with respect to the disc proper for purposes of clarity as it would be very difficult to show them in as fine and thin coatings as are actually applied.

Heretofore those who desired to have records made for their private use, rather than for general sale, have been unable to make them satisfactorily in their homes, and have been compelled to go to some phonograph record making laboratory at considerable expense. Nothing simple, cheap and efficient enough at least in so far as I am aware, has been available for the amateur for use in his own home. By my improved method I propose to make a record blank which can be purchased as an article of manufacture upon the open market just as finished records are bought at the present time.

All of the record blanks with which I am familiar and which might be considered as available for amateur recording have been made of wax which, when reproduced, rapidly wear out.

Briefly stated my improved blank consists of a hard supporting ground or bed, preferably a disc made of glass, smoothly polished on the side upon which the recording is to be placed and coated on the smooth surface with a very thin film of paraffine or wax. I realize that in the art as it is at present known, it has been suggested to form a blank in the manner thus briefly outlined, but in so far as I am aware no such blank has ever been manufactured or placed upon the market, and where such blanks have been used, the results obtained have been but

partially successful because of certain difficulties encountered in the method which was used in preparing them, which difficulties it is the object of my invention to 5 overcome.

My method of preparing a blank is as follows: A disc 1 preferably made of glass as above stated of the proper size and shape to fit upon the turn table of an ordinary talking machine is provided, on one face at 10 least, with a very smooth surface. The disc is first warmed and then placed with its smooth surface upward and level. Over the smooth surface a definite quantity, 15 determined by the size of the disc, of a solution of paraffine or wax in gasoline or other volatile solvent is poured and allowed to spread until the whole surface is covered. The quantity of the mixture is carefully de- 20 termined to suit the size of the disc and the temperature of the disc and of the solution is maintained so that it will spread evenly over the entire surface of the glass without congealing. If the glass is too cold the 25 wax will congeal against it without spreading and if too hot, evaporation will take place before the spreading is completed. The wax or paraffine 2 might well be applied in pure melted form instead of in solution, 30 but I prefer to use the solution because by so doing it is possible to obtain a much more even distribution of the wax or paraffine and also in much smaller quantities, both of which results are highly desirable.

It is also possible if desired, to apply the film by immersing the disc in a bath of melted paraffine or wax after which it is withdrawn and partially drained. This method of applying the film can be satis- 35 factorily utilized, but I prefer the first method mentioned, namely, the one wherein a solution of wax in a volatile oil is used.

The next step in my method or process is one upon which my experiments show much 40 of the success obtained in the making of a record depends. If the wax or paraffine upon the surface where the recording is to take place, be allowed to stand as applied, until the gasoline has evaporated, cooling 45 from the exposed surface downwardly as it were, there will be a decided tendency to form crystals or nodules in the wax and its adhesion to the glass disc, will not be nearly as great as is desirable. Such crystals or 50 nodules are very objectionable when it comes to the actual recording of the record as the stylus which is used to cut the undulatory groove, in a manner well known to the art, when it encounters one of these crystals or 55 nodules of wax forms a ragged spot in the groove which later, after the record is etched, as will be described, greatly impairs the quality of the reproduced sound. By 60 repeated experiments, I have found that the 65 formation of such crystals or nodules can

be almost entirely avoided by treating the blanks in the following manner.

If the wax has been applied in solution, before the gasoline has evaporated, the disc is removed to a place warmer than the melting point of the pure wax or paraffine as the case may be so that when the gasoline has been entirely evaporated the wax or paraffine remains in a liquid state in a very thin film upon the disc. After this is accomplished 70 the blank is transferred to a level supporting surface which is kept quite cool so that the glass cools first and the wax afterwards and from the unexposed side outwardly, as it were, instead of from the exposed side downwardly or inwardly. In this way the wax 75 congeals first against the glass surface and by so cooling it I have found that a remarkably smooth film may be applied which is given a very perfect adhesion to the disc with 80 a complete absence of crystals or nodules. A very convenient way in which to carry on the cooling in this manner is by "floating" 85 the disc upon cold water as illustrated in Fig. 1, the water 3 being contained in some 90 suitable tray 4.

Of course variations from the exact procedure just described, may be made, either for the sake of convenience or for the sake 95 of quantity production. For instance, the disc may be immersed in the solution instead of having it poured upon it and the surplus removed by centrifugal force produced by rotating the disc on its axis. The gasoline or other volatile solvent might be 100 driven off by "floating" the disc, face up, on melted paraffine. The cooling might also be carried on by floating the disc face up on cold water. But no matter in what manner the film of wax or paraffine may be applied it is of great importance that the recording surface of the blank be cooled first 105 from the side of the disc, otherwise the wax or paraffine will not be deposited or congealed in the fine and even manner which I 110 have described. Of course if some of the methods above outlined were pursued, the disc would become coated with the wax on both surfaces as well as on the edges, but this would in no wise matter provided only 115 that the upper or recording surface be finished with the very fine, thin, smooth film described.

Phonograph record blanks thus prepared are easily handled, packed and transported 120 and do not deteriorate during storage. When it is desired to produce a record, a blank is placed upon the turn table of a machine and a fine filament of the wax is removed by the recording stylus 5 of a suitable recording apparatus 6, which need not 125 be herein described as it forms no part of the present invention, the stylus leaving a fine undulatory line of exposed glass. When this line has been traced, the glass exposed 130

can be easily and quickly etched by using a solution of hydrofluoric acid. This last mentioned step is quite a familiar one and I make no claim to novelty in this part of the process.

In the tracing of records in wax, better results are obtained if the wax be warm enough to be plastic, but not liquid. During the recording or tracing, the wax is more easily and sharply cut by the recording stylus if it be kept suitably warm and furthermore, the portions which are not cut away adhere more firmly to the glass. I have also discovered that the etching is much more perfectly accomplished if the wax be at a plastic temperature during the treatment as well as during the recording process. If too cold, the wax tends to peel from the glass during the etching process. Another matter of importance in producing a successful record by my method is that the stylus with which the recording is done, while it must be hard enough to hold a sharp edge, is very preferably made of some material which is softer than the material of the disc whether it be glass, copper or zinc. If a disc of copper or zinc be used, the sharp point of the stylus will be liable to penetrate not only the wax, but also the metal below at least for a minute distance scraping off filamentary cuttings which collect upon the point of the stylus or are forcibly intruded into the wax film which will cause imperfections in the finished record. My experience indicates that glass is to be preferred as the material from which to make the disc as glass can be given a very hard smooth surface, harder than the material from which the stylus is made, such surface preventing any possibility of the needle cutting into the material of the disc.

The wider the groove is made during the etching process, the less representative will it be of the original tracing recorded upon the blank. Therefore, to secure the most satisfactory results, the undulatory line originally exposed on the surface of the disc must be as fine and narrow as it is possible to make it. This requires a very fine and sharp cutting tool or stylus, the point of which must be held against the surface of the glass with no more than enough pressure to cleanly penetrate the wax so that the dulling effect upon the tool may be reduced to a minimum. This light pressure cannot be depended upon to cut the wax cleanly from the surface of the disc unless it has been applied in a very thin and uniform film which adheres perfectly to the surface at all times until the etching is completed. A blank produced by my method meets the above requirements and makes it practicable to trace or record a line so fine that etching can be carried on to the depth

necessary to hold a phonograph reproducing needle, without becoming so wide as to seriously impair its definition for purposes of sound reproduction.

The record blank heretofore described is suitable for producing single records only. I have, however, carried the process of blank producing farther so as to make a blank suitable for tracing a transparency from which, by photo engraving processes, a die may be produced which can be used as a means for pressing any number of records desired from suitable material such as bakelite. Having prepared a record blank as already described, I cover its surface with a very thin coat of graphite by gently rubbing such substance in flaked or powdered form upon the wax until a smooth very thin crust of graphite is formed. By this means I can produce an opaque film, evenly and thinly distributed as above described, and easily cut away by the recording stylus and the results thus obtained are better and more practicable than those produced in any other way. When such a blank is traced by a recording stylus such as I employ, a cut is made through both graphite and wax, as shown in Fig. 5, the wax being translucent but the graphite opaque. The transparent line where the graphite is cut away is very sharply defined and is readily adapted for use as a transparency in the making of dies for pressing a plurality of records by any one of a number of suitable processes, as above suggested, but which are not here described as they form no part of this invention.

It is important in making a transparency that the wax be translucent otherwise the full width of the groove which is cut by the V-shaped end 9 of the stylus will not be effective during the photo-engraving. I realize, of course, that it has already been proposed to make transparencies for photo-engraving purposes but in so far as I am aware none of the blanks have been made in accordance with this method. In some cases lamp black has been applied directly to a glass disc but this scheme is open to objection because the physical characteristics of lamp black are such as to cause the recording stylus to expose an undulatory line of glass which is too ragged to give satisfactory results. In my method, however, where graphite is applied in the shape of a thin crust, a very clearly defined line is cut entirely through it into the film of translucent wax below.

I wish it to be understood of course that a transparency made in accordance with the method herein disclosed may be used not only for preparing mechanical records as indicated but also for producing any other type of record for reproduction purposes, for example records acting as transparen-

cies upon a beam of light which is used in connection with a selenium cell.

I claim:—

1. The method of preparing a phonograph record blank for recording purposes which consists in warming the disc or plate, in applying a film of melted wax, and in cooling the disc or plate before cooling the exposed surface of the melted wax.
- 10 2. The method of preparing a phonograph record blank which consists in applying a solution of wax in a volatile solvent to the surface of a smooth disc or plate, in heating the plate to the melting point of the wax, and in cooling the plate to congeal the wax from the unexposed side outwardly.
- 15 3. The method of preparing a phonograph record blank which consists in covering the surface of the disc or plate with a solution of wax in a volatile solvent, in floating the disc upon melted wax until the solvent has evaporated, and in cooling the blank by placing it upon cold water.
- 20 4. As a new article of manufacture, a record blank comprising a disc of glass hav-

ing a covering of wax and one of graphite thereover.

5. As a new article of manufacture, a record blank comprising a disc of glass having a covering of translucent wax and a superimposed crust of graphite.

10 6. The method of preparing a phonograph record blank for recording purposes which consists in applying a film of liquid wax to a warm disc or plate and in congealing the wax by cooling the plate while keeping the outer surface of the wax exposed to a melting temperature.

15 7. The method of preparing a phonograph record blank for recording purposes which consists in applying a film of liquid wax to a warm and hard supporting ground or bed and in congealing the wax by cooling the supporting bed while keeping the outer surface of the wax exposed to a melting temperature.

20 In testimony whereof, I have hereto signed my name.

WILLIAM M. VENABLE.
